INVENTOR

Frank P. Bunker,
BY Maurice Leo.

ATTORNEYS

UNITED STATES PATENT OFFICE.

FRANK P. BUNKER, OF NORTH MANCHESTER, INDIANA.

MOLD.

Application filed March 4, 1924. Serial No. 696,862.

To all whom it may concern:

Be it known that I, FRANK P. BUNKER, a citizen of the United States, and resident of North Manchester, in the county of 5 Wabash and State of Indiana, have invented certain new and useful Improvements in Molds, of which the following is a specification.

My invention relates to improvements in 10 collapsible brick molds, and it consists in the combinations, constructions and arrangements herein described and claimed.

More specifically, the present invention is 15 an improvement over that disclosed in Letters Patent of the United States 1,268,676 granted to me June 4th, 1918, or an improved brick mold, and contemplates the provision of a brick mold comprising separable side and end members and partitions, 20 the side and end members being adapted to be removed from bricks which are formed in the mold to rest upon a pallet without there being any necessity of removing the partition from positions between the bricks, 25 whereby the bricks with the partitions therebetween may remain on the pallet until the bricks are cured while the side and end members may be used with other partitions and pallets to form additional bricks.

30 A further object of the present invention is to provide a collapsible brick mold having the side members and the end members thereof provided with novel cooperative locking elements for releasably holding the side and end members in assembled position 35 and for preventing lateral displacement of the partitions of the mold so long as the side and end members of the mold are in assembled position.

40 A further object of the invention is the provision of cooperative molds and pallets, the pallet having means engaging with the mold when the latter is assembled tending to hold the mold in centered position on the 45 pallet without preventing separation of the end members of the mold from the side members thereof when desired.

Other objects and advantages will be apparent from the following description, considered in conjunction with the accompanying drawings, in which—

Figure 1 is a perspective view showing a

mold embodying the present invention in position for use on a pallet,

Figure 2 is an elevation of one of the end 55 members, showing the normally inner wall of the latter,

Figure 3 is a view similar to Figure 2, showing the inner wall of one of the side 60 members,

Figure 4 is a relatively enlarged fragmentary perspective view of a corner portion of the mold, showing cooperative side and end members in slightly spaced apart relation, and

Figure 5 is a fragmentary top plan view showing the mold in position on the pallet.

A mold embodying the invention in the form now preferred by me comprises a pair of end members 1 and a pair of side members 2. Each end member 1 is substantially rectangular and is provided at each of its opposite ends with an upper substantially hook-shaped or right angular locking extension 3 and a lower similar locking extension 4. The bill portion of each of the substantially hook-shaped locking extensions 3 and 4 extends downwardly from the body of the locking extension. The inner wall of the bill portion of each of the locking extensions 3 is inclined upwardly and inwardly from its lower end as indicated at 3^a. Likewise, the inner walls of the bill portions of each of the locking extensions 4 are inclined upwardly and inwardly from its 85 lower end as indicated at 4^a. The upper locking extensions 3 extend from the upper corner portions of each end member 1 in the plane of the end member while the lower locking extensions 4 extend from the lower 90 corner portions of the end member.

The side members 2 are adapted to cooperate with the end members 1. Each of the side members 2 is substantially rectangular and is provided at each of its opposite ends with 95 an upper substantially hook-shaped or right angular locking extension 5 and with a lower similar locking extension 6. Each of the locking extensions 5 or 6 has the bill portion thereof extending upward from its juncture with the body of the locking extension. The inner wall of each locking extension 5 is inclined downwardly and inwardly from its upper end as indicated at

5^a and the inner wall of each of the bill portions of each of the locking extensions 6 is similarly inclined from its upper end as indicated at 6^a.

5 The respective locking extensions on the end members 1 are adapted to engage with the corresponding locking extensions on the side members 2 so that the side members and the end members will be releasably held 10 in position to provide a frame that is rectangular in horizontal sectional contour and has vertical end and side walls. Since the inner walls of the bill portions of co-engaging locking extensions are inclined as described, the meeting portions of adjacent side and end members of the frame will be drawn tightly against each other when the cooperative locking extensions of such side and end members are engaged with each 15 other. The side and end members therefore will be tightly connected together at the corners of the frame and at both the upper and lower ends of the frame.

The inner faces of the end members 1 preferably are smooth while the side members 2 are provided with spaced apart vertical grooves 7 in their inner faces extending the full height thereof, corresponding grooves 7 of the two side members being in alignment transversely of the frame and being adapted to engage with the end portions of a substantially rectangular partition 8 which is slidable vertically in the frame.

Each of the end members 1 is provided 35 with a horizontal lug or strip 9 on the outer face of the end member, the lug or strip 9 being adapted to serve as a handle or hand hold.

A pallet for use with the frame is indicated at 10 and has a flat upper face, preferably, although not necessarily, comprising an upper face plate of a suitable metal, such as sheet iron, secured upon a wooden base. An elongated stop or bumper 11 is secured 40 on the pallet 10 in proximity to one longitudinal edge of the latter and in parallel relation to such longitudinal edge. A similar stop or bumper 12 is secured upon the pallet 10 in proximity to one transverse edge 45 of the pallet and in spaced parallel relation to said transverse edge. The arrangement is such that the frame will be disposed substantially in centered relation on the pallet with 50 one of the end members thereof against the stop 12 and one of the side members thereof against the stop 11.

From the foregoing description of the various parts of the device, the operation 60 thereof may be readily understood. The interior of the mold comprising the frame resting upon the pallet in the manner described is divided by the partitions 8 into a plurality of compartments, each open 65 at its upper end and into which brick

forming material may be placed to form bricks of a desired size. While in practice, the spacing between the side walls of these compartments will be such that the bricks will be formed flatwise therein, it is obvious 70 that provision may be made for forming the bricks edgewise simply by spacing the grooves 7 of each side member 2 apart so that the height of each of the compartments of the mold will be greater than the width 75 thereof. Also, it will be manifest that the size of the bricks which are to be formed may be varied by varying the spacing between the grooves 7 of each side member of the frame and if so desired, the grooves 7 may be omitted and the inner faces of the side members 2 formed smooth so that a mold adapted for use in forming one large block 80 of any suitable material will be provided.

After the compartments of the mold have been filled with brick forming material, the handles or hand holds 9 of the end members may be grasped and the end members may be lifted bodily until the cooperative locking extensions of the end and side members are in such position in respect to each other that the end and side members may be separated simply by moving such members laterally outward. The molded bricks spaced apart by the partitions 8 may remain on the pallet 10 until hardened and cured while the side and end members may be used without delay with other partitions 8 and other pallets 10 in forming additional bricks.

Obviously, my invention is susceptible of embodiment in forms other than that illustrated in the accompanying drawings and I therefore consider as my own all modifications and adaptations of the form of the device herein disclosed as fairly fall within the scope of the appended claims.

I claim:

1. In a mold of the character described, a pair of substantially rectangular side members, each having an upper hook-like extension and a lower hook-like extension at each of the opposite ends thereof, the bill portion of each hook-like extension depending from its juncture with the body of the extension, and a pair of substantially rectangular end members cooperating with said side members, each end member having an upper hook-like extension and a lower hook-like extension at each of the opposite ends thereof for engaging with the corresponding hook-like extensions at one end of one of the side members, the bill portion of each hook-like extension to an end member depending from its juncture with the body of the hook-like extension.

2. In a mold of the character described, a pair of substantially rectangular side members, each having an upper hook-like extension and a lower hook-like extension at each

of the opposite ends thereof, the bill portion of each hook-like extension depending from its juncture with the body of the extension, and a pair of substantially rectangular end members cooperating with said side members, each end member having an upper hook-like extension and a lower hook-like extension at each of the opposite ends thereof for engaging with the corresponding hook-like extensions at one end of one of the side members, the bill portion of each hook-like extension to an end member depending from its juncture with the body of the hook-like extension, and the inner walls of the bill portions of co-engaging hook-like extensions being oppositely inclined.

FRANK P. BUNKER.
